UNITED STATES PATENT OFFICE.

WILLIAM P. PITTS, OF KANSAS CITY, MISSOURI, ASSIGNOR TO IRVING-PITT MANUFACTURING COMPANY, OF KANSAS CITY, MISSOURI, A CORPORATION OF MISSOURI.

LOOSE-LEAF BOOK.

Application filed September 19, 1921. Serial No. 501,526.

To all whom it may concern:

Be it known that I, WILLIAM P. PITTS, a citizen of the United States, residing at Kansas City, in the county of Jackson and 5 State of Missouri, have invented a certain new and useful Improvement in Loose-Leaf Books, of which the following is a specification.

My invention relates to improvements in 10 loose leaf books of the type provided with conjointly swinging hook plates having ring hooks for supporting loose leaves.

One of the objects of my invention is to 15 provide a loose leaf book of the kind described, which is simple, cheap to make, which is durable and not liable to get out of order, which can be easily repaired, and which has an attractive appearance and is efficient in operation.

20 My invention provides further a novel spring plate which forms with the back of the book a housing for holding and protecting the hook plates.

25 My invention provides still further novel means for pivotally supporting the hook plates in the spring plate.

My invention provides further novel 30 means for attaching the spring plate to the back of the book.

35 The novel features of my invention are hereinafter fully described and claimed.

In the accompanying drawing which illustrates the preferred embodiment of my invention,

Fig. 1 is a perspective view of my improved loose leaf book, portions of the covers being broken away.

Fig. 2 is an enlarged bottom perspective view of the spring plate and hook plates 40 mounted therein.

Fig. 3 is an enlarged cross section on the line 3—3 of Fig. 1.

Fig. 4 is an enlarged cross section on the line 4—4 of Fig. 1, the hooks being shown 45 in the open position.

Similar reference characters designate similar parts in the different views.

1 designates the back of a book provided with the usual covers 2 flexibly connected 50 therewith.

Attached to the inner side of the back of the book is an inverted box shaped spring plate 3, open at its back and having side walls comprising longitudinal flanges 4, 55 which extend toward and preferably against

the back 1. The spring plate is provided at its ends with two end flanges 5, which extend to the back 1, and are provided each with a longitudinal extension 6 which is secured in any suitable manner to the back 60 1, as by a rivet 7, which extends through the back and through a hole 8 in the extension 6.

Mounted in the housing formed by the spring plate 3 and back 1, are two longitudinal hook plates 9, each having rigidly secured to it hooks 10 arranged to form, with the hooks of the other plate, rings for supporting detachable loose leaves.

The adjacent edges of the hook plates 9 70 are interlocked in any suitable manner so as to swing conjointly, as by means of double headed buttons or rivets 11, mounted in cooperating recesses 12 in the inner edges of the plates 9, the heads of the buttons or 75 rivets 11 being respectively above and below the plates 9.

The outer edges of the plates 9 bear 80 against the inner sides of the flanges 4, intermediate of the top of the plate 3 and inwardly extending obliquely inclined projections 13 one or more of which are provided in each flange 4. The flanges 4 exert a pressure inwardly against the hook plates 9 which holds the hook plates interlocked 85 with each other and in either the open or closed position. The spring plate is provided with lateral notches 14 through which respectively extend the hooks 10. The projections 13 hold the hook plates in their 90 proper operative positions. By having the projections 13 inclining inwardly and upwardly, and the inverted box-shaped plate being open at its back, the hook plates 9 can be readily slipped into their operative 95 positions between the flanges 4 in which positions they will be securely held without further operation.

In attaching the spring plate to the back, after the hook plates have been mounted into position, it is but necessary to insert the rivets 7 through the back and extension 6 and upset the inner ends of the rivets.

By having the side flanges 4 parallel, flat 105 and at right angles to the back of the book, as shown, and by having the projections 13 punched inwardly from the side flanges, with their inner sides inclining inwardly and toward the top portion of the spring plate 3, a wide base for resting against the 110

back of the book is provided, thus reducing liability of the attaching means being broken away in use, and enabling the hook plates being readily inserted while interlocked into their operative position.

I do not limit my invention to the structure shown and described, as many modifications, within the scope of the appended claims, may be made without departing from the spirit of my invention.

What I claim is.

1. In loose leaf supporting means of the kind described, a spring plate having side flanges provided on their inner sides with projections spaced from the top of the plate and on their inner sides inclining inwardly and toward the top of the plate, and two interlocked leaf engaging members respectively operatively engaging at their outer edges said flanges and held in operative position by and between said projections and the top portion of said plate.

2. In loose leaf supporting means of the kind described, a spring plate having two flat parallel side flanges adapted to rest at

their edges at right angles against the back of a book, the flanges on their inner sides having projections which are spaced from the top of the plate and which on their inner sides incline inwardly and toward the top portion of the plate, and two interlocked leaf engaging members respectively operatively engaging at their outer edges said flanges and held in their operative position by and between said projections and the top of the plate.

3. In a loose leaf supporting means of the kind described, a spring plate having two flat parallel side flanges and means for attachment to the back of a book, the flanges having punched inwardly therefrom projections spaced from the top portion of the plate and adapted to have their upper ends form supports for hook plates, the inner sides of said projections inclining inwardly and upwardly, the flanges adapted to have their edges rest against the back of a book.

In testimony whereof I have signed my name to this specification.

WILLIAM P. PITTS.
